UNITED STATES PATENT OFFICE.

CYRUS TOBIAS, OF FREEPORT, ILLINOIS.

HARNESS-CRUPPER.

SPECIFICATION forming part of Letters Patent No. 233,715, dated October 26, 1880.

Application filed July 16, 1880. (No model.)

To all whom it may concern:

Be it known that I, CYRUS TOBIAS, of Freeport, in the county of Stephenson and State of Illinois, have invented an Improved Crupper 5 per for Harness, of which the following is a specification.

The object of my invention is to furnish a crupper of improved construction, combining the advantages of rigidity, lightness, smoothness, coolness, cleanliness, durability, and cheapness.

Cruppers have been constructed of metal frames covered with leather, and of caoutchouc cast hollow, so as to form an air-space within; 15 but these devices are not satisfactory, as the metal frames are solid, and therefore weighty, and the leather covering and caoutchouc too heating and not cleanly in use.

My improved crupper consists of a hollow 20 sheet-metal body having its ends open for the reception of the attaching-straps, which are secured by rivets.

In order that my invention may be fully understood, I will proceed to describe it with 25 reference to the accompanying drawings, in which—

Figure 1 is a plan view of my improved crupper, partly in section, on the line 1 1, Fig. 2, so as to exhibit the mode of attaching the

straps. Fig. 2 represents a section on the line 30 2 2, Fig. 1, showing the thin shell of the crupper.

A represents the body of the crupper, which conforms to the most approved and common construction, and is made hollow, of sheet-zinc 35 or other metal.

B are the attaching-straps, which are inserted three-fourths of an inch, more or less, in the open ends a a of the crupper, and are secured by rivets C C. 40

This crupper is as simple and convenient in use as the ordinary crupper, and more economical, owing to its great durability. It is cleanly in use, and, being light in weight, it is much cooler than others heretofore constructed, and 45 is not liable to be affected by or to chafe the animal, like leather.

Having thus described my invention, what I claim, and wish to secure by Letters Patent, is— 50

The hollow sheet-metal crupper A, having attaching-straps B B secured in the open ends a a by rivets C C, as and for the purpose set forth.

CYRUS TOBIAS.
